(57) **CLAIM**

The ornamental design for a neck tie, as shown and described.

DESCRIPTION

FIG. 1 is a front perspective view of a neck tie according to the present invention.

FIG. 2 is a front perspective view of the neck tie illustrated in FIG. 1 and showing fastening elements in a disengaged position.

FIG. 3 is a front elevation view of the neck tie illustrated in FIG. 1.

FIG. 4 is a rear elevation view of the neck tie illustrated in FIG. 1.

FIG. 5 is a top plan view of the neck tie illustrated in FIG. 1.

FIG. 6 is a bottom plan view of the neck tie illustrated in FIG. 1.

FIG. 7 is a left side elevation view of the neck tie illustrated in FIG. 1; and,

FIG. 8 is a right side elevation view of the neck tie illustrated in FIG. 1.

The broken lines depict fastening elements of the neck tie that do not form a claimed feature of the present invention.
